UNITED STATES PATENT OFFICE.

FLOYD A. RUCKMAN, OF COLUMBIA CITY, INDIANA, ASSIGNOR TO JOHNSON ACETYLENE GAS COMPANY, OF CRAWFORDSVILLE, INDIANA, A CORPORATION.

RESERVE MAGAZINE AND SIGNAL.

1,306,355.

Specification of Letters Patent. Patented June 10, 1919.

Application filed February 6, 1918. Serial No. 215,673.

To all whom it may concern:

Be it known that I, FLOYD A. RUCKMAN, citizen of the United States, residing at Columbia City, in the county of Whitley 5 and State of Indiana, have invented certain new and useful Improvements in Reserve Magazines and Signals; and I do declare the following to be a full, clear, and exact description of the invention, such as will enable others skilled in the art to which it 10 pertains to make and use the same.

My invention relates to acetylene generators and its object is to provide a reserve carbid magazine which will operate to dim 15 the lights at intervals thereby providing a signal which indicates that the supply of carbid in the main magazine has been exhausted and the apparatus needs refilling.

Another object of my invention is to provide 20 a reserve magazine of this character in which means are provided to discharge a sufficient amount of carbid from the reserve magazine, at intervals as to allow the apparatus to operate for a period from the carbid 25 which will be discharged into the main magazine.

Another object of my invention is to provide 30 a magazine of this character all parts of which are readily accessible and may be easily removed and cleaned and which is so constructed that the maximum of use will be obtained with a minimum of wear of the parts thereof.

To this end my invention resides in the 35 novel combination, construction and arrangement of parts to be more fully herein-after described and claimed when taken in connection with the accompanying drawings which form a part of this application and in 40 which:

Figure 1 is a vertical sectional view of 45 a generator equipped with my reserve magazine;

Fig. 2 is a detail vertical sectional view of the magazine on an enlarged scale;

Fig. 3 is a horizontal sectional view on the line X—X of Fig. 2.

Briefly described my invention comprises substantially a reserve carbid magazine suitably mounted in the main carbid magazine of a generator. The reserve magazine is provided with a valve and operating mechanism therefor to discharge the reserve supply at intervals after the supply of carbid 50 in the main magazine has become entirely exhausted. Means are also provided where-

by the discharge of carbid from the reserve hopper is augmented so that the carbid will be discharged into the main magazine and the machine will then operate for a period 60 when the carbid discharges from the main magazine.

Referring more particularly to the drawings in detail in which like reference characters indicate like parts I have shown and 65 described my reserve magazine as applied to an acetylene generator of the pit type which is constructed of the usual generator casing C embedded in the earth and having mounted therein the ordinary form of gas 70 bell B below which is secured on the inner shell S of the generator a suitable type of main carbid magazine M. This main magazine M is provided with a suitable valve mechanism to operate the same whereby to 75 discharge the carbid from the magazine when the gas bell is lowered as the pressure of the generated gases decreases in the interior of the machine. In this preferred form I have shown a valve of the main car- 80 bid magazine as being operated by a push rod P which extends above the magazine and is adapted to be forced downwardly by the lowering movement of the gas bell.

Suitably mounted and preferably centrally located within the main magazine and supported on suitable brackets A, secured on the inner walls of the main magazine, is my improved reserve magazine, which comprises a substantially cylindrical hopper 1 85 provided with an inclined contracted mouth or funnel 2 and having a casing 3 extended downwardly around the mouth of the hopper and spaced for a considerable distance therebelow. This casing is cylindrical to 90 conform to the shape of the hopper body 1 and may be formed integrally therewith or secured thereto in any suitable manner. The function of this casing is to protect the operating parts of the valve mechanism of the 95 reserve magazine in a manner to be herein-after described. The upper end of the hopper is open and is provided with a diametrically disposed metal bar 4 extended there-across and suitably secured to the upper end 100 of the hopper and on this bar a pair of retaining nuts 5 serves to secure a cylindrical pipe or casing 6 depending from the bar 4 with its lower end spaced below the top of the hopper and provided with a bottom 7 105 which is suitably secured or threaded thereon, and centrally apertured to receive

therethrough a valve operating rod 8. The diametrically extending bar 4 is provided at its central portion with an aperture in alignment with the aperture disposed in the bottom 5 to receive and guide the rod 8 therethrough. The operating rod 8 is vertically movable within the hopper and has its upper end extending above the top of the hopper and through an aperture provided in the 10 lid of the main carbid magazine and projecting slightly above for a purpose to be hereinafter described.

Pivots mounted on the lower end of the operating rod 8 and spaced slightly below 15 the mouth of the hopper is a receptacle or valve 9 which is preferably pan-shaped and is pivotally secured thereon by means of a pin 10 extended through the lower end of the rod 8 and journaled in a pair of lugs 11 20 formed on the bottom of the receptacle 9 and secured thereto in any suitable manner. The bottom of the receptacle 9 is apertured to permit of the passage of the rod 8 therethrough for its pivotal connection with the 25 receptacle, the aperture being of sufficient dimension to permit of relative movement of the receptacle with respect to the rod. This receptacle 9 is normally disposed in a horizontal plane below the mouth of the hopper 30 and supported in said plane by means of a depending strap or link 12 secured at one end to a lug 13 formed on the mouth portion 2 of the hopper and suitably secured at its outer end to one end of the receptacle. The 35 other end of the receptacle or pan is open and adapted for the discharging of carbid therethrough.

Coacting with the rod 8 and strap 12 and serving as a further means for retaining the 40 pan or receptacle 9 in its horizontal position is an expansion coil spring 14 surrounding the rod 8 and disposed within the casing 6 and having its upper end bearing against a sleeve member 15 slidably mounted on the 45 rod 8 and positioned within the aperture formed in the diametrically disposed bar 4 and provided with a suitably enlarged head to engage the end of the spring. On the upper end of this sleeve 15 is seated a wing 50 nut 16 which is suitably threaded on the upper end of the valve-rod 8 at a point spaced above the diametrically extending bar 4 so that the sleeve will be forced downwardly against the coil spring by the nut 55 when the valve-rod is actuated.

Arranged within the casing 3 and suitably secured in the walls of the casing is a substantially funnel-shaped member 17 spaced below the receptacle 9 and having its contracted bottom portion disposed adjacent one 60 side of the magazine. Pivots mounted on the bottom portion of the funnel member 17, as shown at 18, is a flat plate or trap door 19 constituting a closure for the primarily open 65 lower end of the funnel member 17, and the

parts 17 and 19 provide a collecting receptacle disposed in the casing 3 below the mouth of the reserve magazine. The closure plate 19 is normally held against the bottom of the funnel member 17 by means of a 70 weight 20 disposed at one end of the plate which weight may be varied to suit individual conditions as desired.

In the operation of my magazine, when the supply of carbid in the main magazine 75 has been entirely exhausted, the gas bell settles lower and, the pressure of the gas within the machine being decreased, the lights will be dimmed and thereby act as a signal to indicate that the main magazine needs re- 80 filling. When the bell is lowered a sufficient distance the top of the bell will come into contact with the upper projecting end of the operating rod 8 which is normally disposed at a lower level than the upper end of the 85 main magazine valve operating rod and which will be forced downwardly under action of the bell to open the valve 9 at the mouth of the reserve magazine. Owing to the spaced relation of the valve 9 from the 90 mouth of the hopper a considerable amount of carbid will be held thereon exteriorly of the hopper and when the operating rod 8 is forced downwardly against the action of the 95 spring 14, the valve 9 will be tilted toward its open end and the carbid will then flow therefrom into the lower receptacle, formed by the funnel member 17 and the closure plate 19. This allows carbid to pass from the hopper to the valve 9 and the flow will 100 continue until a sufficient amount of carbid has accumulated in the lower receptacle, to overbalance the weight 20, whereupon the closure plate or trap door will swing away from the lower end of the funnel member, 105 and carbid will be precipitated therethrough and into the main magazine and thence into the generating chamber, whereupon a sufficient amount of gas will be generated to lift the bell clear of the valve-rod which will 110 then be forced upward by action of the spring 14 to bring the receptacle or valve 9 again into a horizontal position, thereby effecting a closure of the mouth of the 115 reserve magazine.

The carbid precipitated by this action through the funnel member 17 is more than sufficient to raise the bell B above the valve-rod P, so that the valve of the main receptacle M closes before all this supplemental charge has passed therethrough and part of this charge is retained within the main magazine, and the apparatus will operate for a period on the reserve quantity of carbid which will be discharged from the main magazine through the action of the bell B on the rod P and the valve operated by the latter.

If it were not for the funnel shaped member disposed below the mouth of the reserve 130

magazine to act as a retarder for the carbid, the gas bell would settle or remain approximately stationary on the operating rod of the reserve magazine, and cause a continual slow 5 dribble of the carbid from the reserve magazine with a consequent continual dimming of the lights, which is very undesirable. Owing to the construction which I have just described, there will be only a momentary 10 dimming of lights, and this dimming will be repeated at intervals; and at each operation of the reserve magazine an over-charge of carbid will be discharged therefrom which will accumulate in the main 15 magazine and thereby permit the machine to operate for a period by the operation of the valve of the main receptacle.

The spring 14 is of sufficient strength to counteract a considerable part of the weight 20 of the gas bell, which will serve to decrease the pressure of the gas and thus dim the lights in the manner described, until the reserve magazine has discharged into the main magazine. By means of this wing- 25 nut 16 and the rod 8, the valve 9 may be tilted upward or downward from its horizontal position so as to increase or decrease the amount of pressure necessary to cause it to discharge its load of carbid, this resulting 30 in varying the degree to which the lights are dimmed.

While I have shown and specifically described certain details of construction and materials used in the operation of my invention, I do not wish to 35 limit myself to these details and the construction as described herein, as this is merely the preferred embodiment of my invention, but such changes may be made in 40 the details of construction and in the materials used as come within the scope of the appended claims.

Copies of this patent may be obtained for five cents each, by addressing the "Commissioner of Patents, Washington, D. C."

I claim:

1. In an acetylene generator, a main carbid magazine having an outlet, a feeding device for controlling the passing of carbid through said outlet, a reserve carbid hopper having an outlet above the outlet of said main carbid magazine, a feeding device for controlling the passing of carbid through said outlet of the reserve carbid hopper, and an automatically dispensing receptacle between the first said feeding device and the second said feeding device, said receptacle having a trap-door and having means to hold the latter yieldably in a closed position, said trap-door being adapted to receive and support an accumulation of carbid from the feeding device of said reserve carbid hopper and to discharge said accumulation in a unitary mass through the outlet of said main carbid magazine.

2. In an acetylene generator, a main carbid magazine, a valve mechanism to control the discharge thereof, a reserve magazine above the valve mechanism of said main magazine, a valve mechanism for said reserve magazine, and a receptacle between the first and second said valve mechanisms, said receptacle having a bottom pivotally connected to the body thereof, said bottom being provided with means to normally hold it up but being adapted to swing down on its pivot so as to open the receptacle when a predetermined quantity of carbid has been received thereby from the said reserve magazine.

In testimony whereof I have hereunto set my hand in the presence of two subscribing witnesses.

FLOYD A. RUCKMAN.
